BARGE TIPPLE

John H. Bernhard, Omaha, Nebr.

Application May 22, 1951, Serial No. 227,728

8 Claims. (Cl. 114—0.5)

1

This invention relates to the unloading of barges and more particularly it is an object of this invention to provide a barge tipple of novel construction.

At the present time barge cargoes are being loaded and unloaded by stevedore and by crate-by-crate methods. These expensive methods have been thought necessary.

It is an object of this invention to provide barges equipped with cargo cars which can be rolled from the barge to a dock. This has been hitherto thought impractical because of the varying positions of barges relative to docks, the positions varying because of variations in the water level of rivers and because the freeboard of a barge varies with different amounts of cargo and changes during the process of cargo transfer.

It is a particular object to provide a dock having unyielding securing means such as an outwardly projecting ledge disposed above water level in combination with a barge designed to have a side thereof received under the ledge to prevent the raising of the inward side of the barge and in further combination with means for raising the level of the barge relative to the dock whereby the inner side of the barge will be caught beneath the ledge and held at a constant level with respect to the ledge for facilitating unloading of the barge by any method.

A further object of the invention is to provide cargo cars in the combination just described, the cars being rolled from the barge on their own wheels.

A still further object is to provide a method of unloading the cargo cars which comprises the raising of the outer side of the barge to a higher level than the ledge-held inner side of the barge whereby the cargo cars can be rolled by gravity onto a dock surface disposed above the ledge.

A still further object is to provide a barge with means, such as a ballast tank system, for raising and lowering the barge with respect to the water level to cause said barge to be held by said ledge and more particularly to raise the level of the outer side of the barge with respect to the inner side thereof for causing the barge to tilt for employing gravity to roll the cars onto the dock.

Still another object is to provide a locked basin having a water level control system in which a barge is confined during loading or unloading whereby the controlled rising of the water level in the basin causes the barge to be caught by the ledge and subsequently to tilt.

Another object is to provide a multi-deck barge and a dock designed for the unloading of the various deck levels thereof.

2

Still further objects of the invention are to provide a method of and means for: eliminating or greatly reducing the labor cost of stevedoring; reducing the shore or idle time of the barge; reducing or eliminating crating, tallying, checking, pilfering, dispatching, mixing and confusion of cargo; greatly reducing ultimate cost of insurance; providing greater freedom in selection of terminal sites; and finally for speedier dispatch of cargo.

Yet another object of the invention is to provide a device for the purpose described which is sturdy and durable in construction, reliable and efficient in operation, and relatively simple and inexpensive to manufacture, assemble and utilize.

Other and further objects and advantages of the present invention will be apparent from the following detailed description and claims and are illustrated in the accompanying drawings which show the principles of the invention and a mode in which I have contemplated applying those principles.

Other embodiments of the invention utilizing the same or equivalent principles may be used and structural changes may be made as desired by those skilled in the art without departing from the present invention and the purview of the appended claims.

In the drawings:

30 Figure 1 is a cross section view of a barge, diagrammatically shown floating in a basin of controllable water level. A cross sectional view of a portion of a dock having an outwardly protruding ledge is shown, the ledge overlapping the inner side of the barge. A cargo-discharging position of the barge is shown in dotted lines. A cargo car is shown in full lines in an in-transit position and in dotted lines in a position preparatory to the discharge of the cargo car by rolling downwardly onto the dock.

35 Figure 2 is a top plan view of a lock basin system of the invention, a barge being shown in full lines opposite a ledge, subsequent positions of the barge being shown opposite other ledges for the interlocking of other decks of the barge when a multi-deck barge is used.

40 Figure 3 is a top plan view of a multi-deck barge, a portion of the upper deck being broken away, a portion of the ledge of a dock being shown overlapping a side of the barge.

45 Figure 4 is a detailed side elevation of a locking mechanism for holding one of the cargo trailers in place while the barge is in transit.

50 Figure 5 is a side elevation of the barge of Figure 3, forward and rearward side wall portions

thereof being broken away for showing the water inlet and pumping system used to control the level of the barge.

Figure 6 is a view-in-section taken along the line 6—6 of Figure 2 and showing a multi-deck barge in a position preparatory to the unloading of the cargo cars on its lower deck, the barge in Figure 6 being shown under the dock ledge.

Figure 7 is a view-in-section taken along the line 7—7 of Figure 2 and showing a barge in a position preparatory to the discharge of cargo cars on the upper deck level thereof, the barge of Figure 7 being shown underlapping the dock ledge.

Figure 8 is a view-in-section taken along the line 8—8 of Figure 2 showing a barge in a position preparatory to the discharge of cargo cars on an intermediate deck level thereof.

The basic idea of the tipple of this invention is best illustrated in Figure 1. In Figure 1 a barge 10 is shown floating on the surface of water 12. The water 12 is preferably in a locked basin as will be later described.

The barge 10 is shown in cross section in Figure 1. It will be understood that the barge construction shown in Figure 1 is diagrammatic and for the purpose of illustrating the principles of the invention only. Actually, barges have much bracing and other structural features which, for clarity of illustration, are not shown here.

For the purpose of this showing, the barge 10 has a flat bottom 14 and vertical sides 16. The sides 16 are joined to the bottom 14 by means of beveled portions 18 normally disposed below the water line.

The barge 10 has a horizontal deck 20 spaced above its bottom 14, optionally supported by a vertical wall 22 extending from one end of the barge to the other. The barge is further provided with a false deck 30 disposed above the deck 20 and upheld at the sides by wall members 32. The members 32 are disposed inwardly of the outer side 16 of the barge for a purpose later described.

Above the false deck 30 a grooved covering 36 is provided having a plurality of parallel transverse grooves 38 in the upper surface thereof disposed in positions for receiving the wheels 40 of cargo cars, one of which is generally indicated at 42 in Figure 1. The grooves 38 open on at least one side of the barge for permitting the cargo cars 42 to roll off the barge.

It will be understood that the cargo cars 42 can be of any desired construction and that the car shown in Figure 1 is shown diagrammatically and in simple form for illustrative purposes only. Such cars could have couplings thereon for attachment to the cabs of semi-trailer trucks, if desired.

In further accordance with this invention the locked basin is provided with a dock generally indicated at 50 having an outwardly protruding ledge 52 with a preferably flat undersurface 54. The upper surface 56 of the ledge, which will be referred to as the dock surface, is preferably level.

In operation the barge 10 is placed under the ledge 52 at a time when water level is approximately as shown in Figure 1. The water level in the basin is then raised, causing the barge to move upwardly, impinging the inward side of the barge against the under side of the ledge 52.

As thus described, the inner side of the barge is held from moving upwardly while the rising level of the water 12 in the basin will cause the outer side of the barge to move upwardly into the

dotted line position shown in Figure 1. During this movement the ledge 52 will serve as a fulcrum about which the barge pivots.

When the barge has reached the dotted line position shown at 10 the level of water in the basin is caused to rise no further. The cargo cars 42 will then be permitted to roll downwardly, guided by the grooves 38 off the barge and into the dock surface 56, which latter is disposed in alignment with the bottoms of the grooves 38. It will be understood that this accomplishes the objects in the aforementioned objects.

Details of various ways of employing the principles described in Figure 1 are shown in the subsequent Figures 2 to 8.

Referring now to Figure 2 a river is diagrammatically shown at 60. As the water level in the river 60 is unpredictable and is constantly rising and falling, a lock basin generally indicated at 10 is provided, entering from the river 60 for receiving barges during loading and unloading of their cargoes.

The lock basin 10 can be provided with any suitable locking means. One locking means is diagrammatically shown in Figure 2 and includes a pair of swinging doors 72 which are adapted to be closed against each other or opened wide, automatically, and by means of a lock-controlling mechanism disposed in two housings 76.

30 In the housing 76 motors and other means are provided for causing screw threaded elongated lock controlling members 78 to move inward and outward. The outer ends of the lock gate controlling members 78 are pivotally secured to the respective lock gates 72.

Adjacent the lock basin 10 and preferably upstream therefrom is a water reservoir 80 connected with the lock basin 10 by one or more pipes 82 as shown in dotted lines in Figure 2. 40 The pipes 82 are provided with valves 84 which control the flow of water from the reservoir 80 downwardly to the basin 10.

In the basin 10 a plurality of ledges similar to the ledge 52 in Figure 1 are provided for receiving a multi-deck barge 90 as will be later described.

Referring to Figure 5 a multi-deck barge 90 is there shown. The barge 90 is similar to the barge in Figure 1. Its lower structure is similar. 50 For that reason the same numerals used to describe the barge 10 will be applied to similar parts in the other barge 90. However, the barge 90 has a plurality of vertical columns 92 which extend upwardly from the deck covering 36 to an intermediate horizontal deck 98 and upwardly from the intermediate deck 98 to an upper deck 100. It will be understood that all deck coverings 36, 98, and 100 are provided with grooves 38 similar to the deck covering 36.

60 The barge shown in Figure 5 can be optionally provided with means of its own for raising and lowering its level with respect to the level of the water 12 in the basin and for raising and lowering the level of one side of the barge with respect to the other side thereof.

Such means can include valves 110 disposed on each side of the compartmentation walls 22 and opening into the barge below the water line thereof. The valves 110 are controlled by hand wheels 112 accessible from the upper side of the barge. It will be understood that the valves 110 and wheels 112 are merely diagrammatical representations of a valve system and that any other system serving this purpose could be employed.

75 At the opposite end of the barge 90, and as

best seen in Figure 3, a motor 120 is provided for operating a centrifugal pump 124 which latter has its discharge pipe 126 extending over the adjacent end of the barge for discharging water into the basin. The inlet pipe 130 of the pump 124 is disposed in communication with the bottommost portion of the interior of the barge on one side of the compartmentation wall 22 by means of a vertically disposed pipe 134.

The pipe 134 is secured to the pipe 130 by means of a control valve having a hand wheel 140. Between the said control valve and the pump 124 another pipe 146 is disposed in communication with the pipe 130.

The pipe 146 also has a vertical section 148 leading to the bottom of the barge. Between the sections 146 and 148 is a control valve 149.

In Figure 6 the multi-deck barge of Figure 5 is shown up against a dock having a ledge 150, similar in all respects to the ledge 52 shown in Figure 1. The upper surface 155 of the ledge 150 serves as the upper surface of a dock 152.

In Figure 6 the lower deck 36 of the barge is shown in a position for the unloading of cargo cars therefrom.

In Figure 7 a ledge 158 is shown spaced a considerable distance below the upper surface 160 of the dock whereby the ledge 158 functions in the previously described manner although the upper surface 160 of the dock is disposed opposite the upper deck 100 of the barge.

In Figure 8 a ledge 164 is shown spaced downwardly from the upper surface 170 of the dock a lesser distance than shown in Figure 7 whereby the upper surface 170 is disposed on the same level with the intermediate deck 98 of the barge.

It will be understood that in all the previous description it is the bottom portion of the groove 38 of the various decks of the barge which are preferably exactly on the same level as the upper surface of the respective dock at times when the barge is in unloading position.

In operation the lower deck of the barge can be unloaded alongside the dock 152 shown at the left in Figure 2. The barge is then moved to the dotted line position shown in the center in Figure 2 for the interlocking of the intermediate deck 98 thereof under the dock surface 170. The barge is then subsequently moved to the dotted line position shown at the right in Figure 2 for the interlocking of the upper deck 100 of the dock surface 160.

In Figure 4 means is shown for holding a cargo car in position on the barge during travel.

It will be understood that any locking means can be used and that the one shown is shown as an example for purpose of illustration only. In Figure 4 a pivoting lock arm 180 is shown and is adapted to pivot on a pin 182 secured to the deck 100 of the barge by means of two parallel spaced apart ears 184, a portion of one of the ears being shown broken away in Figure 4.

The arm 180 is provided with a substantially transverse end portion 186 which is shaped for engaging an axle 190 of one of the cargo cars 42. The arm 180 is pulled downwardly by a coiled spring 192 which is attached to the deck 100. The arm 180 is preferably so shaped that it can be manually released from the axle 190 to release the cargo car during unloading of the barge.

As illustrated in Figures 1 and 3, means must be provided for preventing the barge from moving outwardly away from the dock at times when

it is inclined. One example of such means is the pair of capstans 200 and 202 which are disposed respectively on the dock ledge 52 and on the deck 36. A rope 204 is disposed about the capstans 200 and 204 for securing the barge to the dock.

As seen in Figure 3 two pairs of similar capstans 208 and 210 lashed by ropes 212 are shown in the top plan view.

The unloading of the barge will be clear from the above description. The loading of the barge can be accomplished by securing the barge in the same position as shown in Figure 1 and rolling other cargo cars 42 into the position of the cargo cars just removed.

It will be understood that this invention has provided a method of and means for much more economically loading and unloading barges.

From the foregoing description, it is thought to be obvious that a barge tipple constructed in accordance with my invention is particularly well adapted for use, by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

I claim:

1. A barge tipple system comprising: a lockable confining basin opening upon a navigable waterway; means for controlling the water level in said basin; dock means in said basin, said dock means having an upper surface, said dock means having an outwardly protruding ledge having an outwardly extending lower side, said ledge overhanging and protruding outwardly over those portions of said dock means beneath said ledge; a barge having deck means for holding cargo, said barge having an outwardly protruding side portion spaced downwardly from said deck on one side of said barge for reception beneath said ledge and for engaging the underside of said ledge whereby when the other side of said barge is caused to raise upwardly with respect to said ledge as the water level in said basin is raised said protruding side portion of said barge will be raised up vertically until it engages the underside of said ledge and then will be held from rising by said ledge for the pivoting of said barge into a position such that the deck of said barge will be caused to incline from said one side thereof downwardly toward the other side thereof, the construction being such that the dock side of said deck is disposed on approximately the same level with the upper surface of said dock at times when the protruding side portion of said barge is disposed beneath said ledge and said barge is in an inclined position; means for holding said barge adjacent said dock; and wheeled cargo cars transversely disposed on said deck.

2. A barge tipple system comprising: a lockable confining basin opening upon a navigable waterway; means for controlling the water level in said basin; dock means in said basin, said dock means having an upper surface, said dock means having an outwardly protruding ledge having an outwardly extending lower side, said ledge overhanging and protruding outwardly over those portions of said dock means beneath said ledge; a barge having deck means for holding cargo,

said barge having an outwardly protruding side portion spaced downwardly from said deck on one side of said barge for reception beneath said ledge and for engaging the underside of said ledge whereby when the other side of said barge is caused to rise upwardly with respect to said ledge as the water level in said basin is raised said protruding side portion of said barge will be raised up vertically until it engages the underside of said ledge and then will be held from rising by said ledge for the pivoting of said barge into a position such that the deck of said barge will be caused to incline from said one side thereof downwardly toward the other side thereof, the construction being such that the dock side of said deck is disposed on approximately the same level with the upper surface of said dock at times when the protruding side portion of said barge is disposed beneath said ledge and said barge is in an inclined position; and means for holding said barge adjacent said dock.

3. A method of unloading a barge comprising: bringing the barge into a lockable confining basin having controllable water level; locking said basin; bringing the barge up against a dock at a side of said basin; holding the inner side of said barge in a position such that the deck of the barge is disposed adjacent the upper surface of the dock while raising the water level in the basin to cause the outer side of the barge deck to be disposed at a higher level than the inner side thereof while holding said barge inwardly adjacent said dock; and permitting cargo containers on said barge to move by gravity across the inclined deck and onto said dock.

4. A method of unloading a barge comprising: bringing the barge alongside a dock in a locked confining basin; controlling the amount of ballast water in the barge so that the inner side of the barge cargo deck is disposed adjacent the upper surface of the dock; holding the inner side of the barge in approximately the above described position while removing the ballast water to cause the outer side of the barge to rise with respect to the inner side thereof for causing the deck of the barge to incline from the outer side thereof downwardly toward the inner side thereof; and then permitting cargo on said deck to move by gravity downwardly onto the dock.

5. A method of unloading a barge comprising: bringing the barge alongside a dock; controlling the amount of ballast water in the barge so that the inner side of the barge cargo deck is disposed adjacent the upper surface of the dock; holding the inner side of the barge in approximately the above described position while removing the ballast water to cause the outer side of the barge to rise with respect to the inner side thereof for causing the deck of the barge

to incline from the outer side thereof downwardly toward the inner side thereof; and then permitting cargo on said deck to move by gravity downwardly onto the dock.

5 6. A method of unloading a barge comprising: bringing the barge into a lockable confining basin; locking said basin; bringing the barge up to a dock at a side of said basin adjusting the height of the barge to a position such that the cargo deck of the barge is disposed adjacent the upper surface of the dock; securing the barge to the dock so that the barge cannot move outwardly away from the dock unduly; causing the outer side of the barge to rise while preventing the inner side of the barge from rising so as to cause the deck of the barge to incline from the outer side thereof downwardly to the inner side thereof; and then permitting cargo containers on said barge to move by gravity across the inclined deck and into said dock.

10 7. A method of unloading a barge comprising: bringing the barge up to a dock and securing it to the dock; causing the deck of the barge to assume a position such that the inner side 15 of the deck is disposed adjacent the upper surface of the dock and such that the outer side of the deck is disposed at a higher level than the inner side thereof; and then permitting cargo containers on said deck to move by gravity across the inclined deck and onto the said dock.

20 8. A method of transferring cargo between a barge and a dock comprising: controlling the level of the body of water in which the barge rides at the dock; securing the barge to the 25 dock to hold the barge adjacent the dock; and adjusting the position of the deck of the barge with respect to the upper surface of the dock as each item of cargo is transferred thereby to maintain the level of the inner side of the deck 30 at a desired position with respect to said dock.

JOHN H. BERNHARD.
